UNITED STATES PATENT OFFICE.

ELI ODELL, OF WINTERSET, IOWA.

IMPROVEMENT IN CARPENTERS' BENCH-HOOKS.

Specification forming part of Letters Patent No. **156,232**, dated October 27, 1874: application filed September 19, 1874.

To all whom it may concern:

Be it known that I, ELI ODELL, of Winter-
set, in the county of Madison and State of
Iowa, have invented a Carpenter's Bench-
Hook, of which the following is a specifica-
tion:

The object of my invention is to provide a
simple and convenient means of securing
boards and pieces to be planed upon a bench
in such a manner that they will be prevented
from moving in any direction under the pressure
of the plane. It consists in a right-angled
bench-hook, and a bench arranged for receiv-
ing and adjusting the same, as hereinafter
fully set forth.

Figure 1 of my drawing is a perspective
view, illustrating the form and construction of
the hook. Fig. 2 illustrates the manner of ap-
plying and operating the same on a carpen-
ter's bench.

a is the short arm of the hook. *b* is a pin
cast solid therewith, or rigidly attached in
any suitable way, and projects downward to
enter a corresponding hole in the top surface
of the bench. *c* is the long arm of the hook,
forming a right angle with the short arm *a*.

d is a sharp point or spur projecting laterally
from the end of the arm *c*, to be driven into
the object designed to be held and planed on
the bench. *f* is a screw or pin projecting
downward from or through the corner of the
hook, to pass through the bench, and then se-
cured thereto by a nut or key. *A* represents
a carpenter's bench; *B*, a movable board that
is to be held rigidly upon the bench during
the process of planing and dressing. *g* is a
common stop, to prevent a forward longitudi-
nal movement of the board *B*. *h* is a common
pin, to prevent lateral movement. *1 2 3* rep-
resent a series of holes for receiving and ad-
justing the pin *b* on the hook *a c*, which en-
gages the corner of the board *B* to hold it rigid
and secure, so that it cannot lift, turn, or slip
under the pressure of the plane.

I claim as my invention—

The right-angled hook *a c*, having pins *b*
and *f*, and spur *d*, substantially as described,
and for the purposes specified.

ELI ODELL.
